No. 732,200.

PATENTED JUNE 30, 1903.

J. A. LITTLE.

ARMATURE.

APPLICATION FILED SEPT. 20, 1902.

NO MODEL.

UNITED STATES PATENT OFFICE.

JOHN A. LITTLE, OF ST. LOUIS, MISSOURI, ASSIGNOR TO GLOBE ELECTRIC COMPANY, OF ST. LOUIS, MISSOURI, A CORPORATION OF MISSOURI.

ARMATURE.

SPECIFICATION forming part of Letters Patent No. 732,200, dated June 30, 1903.

Application filed September 20, 1902. Serial No. 124,159. (No model.)

To all whom it may concern:

Be it known that I, JOHN A. LITTLE, a citizen of the United States, residing at the city of St. Louis, State of Missouri, have invented a certain new and useful Improvement in Armatures, of which the following is a full, clear, and exact description, such as will enable others skilled in the art to which it appertains to make and use the same, reference being had to the accompanying drawings, forming part of this specification, in which—

Figure 1 is a vertical sectional view taken on line 11 of Fig. 2 looking in the direction indicated by the arrow. Fig. 2 is a longitudinal sectional view. Fig. 3 is a fragmentary view of one of the end members, illustrating the contour of its inner face; and Fig. 4 is an end view of one of the armature-sections detached.

20 The object of this invention is to produce a built-up armature of fragmentary parts which when united and connected will present a harmonious whole, but which will permit of cutting out one or more of the sections 25 thereof in case of the destruction of its or their efficiency without disabling the remaining members and which cutting out will reduce the total efficiency only in proportion to the number of such disabled sections.

30 To that end there are employed a pair of end members or heads 1, provided with the hub portions 2, keyed to the shaft 3 by the keys 4. Said heads are provided on their inner faces with the hollow hub portions 5, upon 35 which are the shoulders 5^a, from the outer circumferential face of which extend a series of radial channels or grooves 6, which channels extend quite to the perimeter of said heads and have parallel side walls, thus permitting the cutting thereof with an ordinary 40 milling-tool, while the intervening elevated portions comprise a series of radial wedges 7, with their wider portions at the circumference. Such channels 6 are cut of sufficient 45 depth to readily accommodate the windings of the core-sections when in position.

Between the heads 1 are a series of sections 8, having a form in cross-section to correspond to said wedge-shaped elevations 7, and 50 projecting laterally therefrom are the cores 8^a, upon which the windings are placed.

When the cores are properly wound, the requisite number of sections are placed in position about the shaft 3 with their inner ends abutting against said shoulders 5^a, with 55 the wedge of each section contacting closely with the lateral projecting face of the next section, as shown in Fig. 1, in which position they are temporarily bound together by any convenient means, such as a sufficient 60 number of bands of hoop-iron, &c., after which a drill is inserted through the openings 9 and the ends of said sections are tapped for the centering-screws 10, one for each section, after which centering- 65 screws are inserted to hold said sections in position and the machine-screws 12 are inserted through the openings 11 and the whole is firmly united together, after which the keys 4 are inserted and connection made to 70 shaft 3.

In the event of one of the sections burning out or becoming disabled from any cause its coil is cut out, skipping the disabled section, and the motor may continue its work with 75 only slight decrease in efficiency.

I am aware that minor changes in the construction, arrangement, and combination of the several parts of my motor can be made and substituted for those herein shown and 80 described without in the least departing from the nature and principle of my invention.

Having thus described my invention, what I claim, and desire to secure by Letters Patent, is—

1. In an armature, a pair of separable supporting members, intervening polar sections of substantially wedge shape in cross-section, and shoulders for holding said sections in position between said supporting members; substantially as described.

2. In an armature, a series of removable polar sections arranged circumferentially, and shoulders for retaining them in position; substantially as described.

3. In an armature, a series of removable core-sections arranged circumferentially, and supporting members with shoulders thereon for retaining them in position; substantially as described.

4. In an armature, a series of armature-sections having integral polar projections at

an angle thereto, and retaining members with projections thereon for retaining them in position; substantially as described.

5. In an armature, a series of armature-
sections having integral polar projections at an angle thereto, head members with hubs thereon forming supporting means therefor, and means for securing them against lateral shifting; substantially as described.

10. 6. In an armature, head-pieces with radial channels therein, a series of removable polar sections arranged circumferentially therebetween, and means for uniting them to the head-pieces; substantially as described.

15. 7. In an armature, a series of removable wedge-shaped pole-pieces, and lateral core-sections projecting therefrom about midway their length and heads with projections thereon forming supports therefor; substantially as described.

20. 8. In an armature, a series of removable pole-pieces with lateral core-sections integral therewith, and heads with inwardly-projecting hubs to which heads said members are connected; substantially as described.

25. 9. In an armature, a pair of heads, radial channels in said heads, and interposed sec-

tions whose windings occupy said channels in part; substantially as described.

10. In an armature, a pair of heads, shoulders on the opposing faces thereof, and polar pieces resting on said shoulders and having lateral projections; substantially as described.

11. In an armature, a pair of heads, shoulders on the opposing faces thereof, channels in said faces, and polar pieces resting on said shoulders and provided with windings which occupy said channels in part; substantially as described.

12. In an armature, a pair of heads, shoulders on the opposing faces thereof, radial channels extending from said shoulders to the circumference thereof and removable polar pieces the windings of which rest in said channels; substantially as described.

In testimony whereof I hereunto affix my signature, in the presence of two witnesses, this 17th day of September, 1902.

JOHN A. LITTLE.

Witnesses:

GEORGE BAKEWELL,
G. A. PENNINGTON.
